UNITED STATES PATENT OFFICE.

VIRGILIUS TACIT AND VALERIU PUSCARIU, OF BUCHAREST, ROUMANIA.

WELL-TUBE-CLOSING APPARATUS.

1,153,973.

Specification of Letters Patent. Patented Sept. 21, 1915.

Application filed October 31, 1913. Serial No. 798,569.

To all whom it may concern:

Be it known that we, VIRGILIUS TACIT and VALERIU PUSCARIU, both subjects of the King of Roumania, and both residing at 5 No. 1 Strada Blanduzici, Bucharest, Roumania, have invented certain new and useful Well-Tube-Closing Apparatus, of which the following is a specification.

Apparatus have already been proposed for 10 shutting down spouting bore holes, but they have generally proved unsatisfactory because in most cases the shutting down is effected too quickly, and further the mechanism for operating same is not adapted to be 15 located at a considerable distance from the bore hole, so that if the spouting liquid or substance catches fire as for instance in the case of petroleum wells, it is impossible to shut it down. In the case of such closing 20 devices a chief object to be achieved is that the bore hole shall be closed very slowly and yet with certainty and with great force.

Spoutings of raw petroleum which contains 25 large quantities of free gas, are generally due to a sudden diminution of pressure on the oil. The liberated gases drive large masses of oil, salt water, sand, gravel and gases with great force and to a great 30 height out of the bore hole and it would be very dangerous to shut down a jet of this kind suddenly. When violent jets are shut down suddenly it often happens that several hundred meters of tubing are simply thrown 35 out of the bore hole. The bore hole must therefore be closed very slowly in order by gradually contracting the bore hole, to first 40 check the surging column of gas and liquid and then to shut it down altogether. Great force is however necessary for this purpose. 45 Since spouting bore holes are very liable to catch fire automatically and in such a case it is absolutely impossible to approach the vicinity of the spot, the closing down apparatus must be such that it may be operated with certainty from a considerable distance.

The present invention has now for its object to provide an apparatus which will satisfy the above stated conditions.

Two embodiments of this invention are 50 illustrated by way of example in the accompanying drawings, in which:

Figure 1 is a longitudinal section of one embodiment showing the apparatus in its open condition. Fig. 2 is a longitudinal sec-

tion, and Fig. 3 is a cross section on the line 55 3—3 of Fig. 2 of a second modification of the apparatus.

On a well tube 1 there is fixed by means of a flange 2 or in any other suitable manner a cross-shaped hollow body 3 having a 60 horizontal cylinder 4. In the cylinder 4 there works a piston 5 which may be packed by means of rings 6 like hydraulic ram pistons. The piston 5 is formed with a bore 7 the axis of which is located in the direction 65 of the tube 1 and has a diameter equal to the diameter of the well tube. On both sides of the bore 7 the piston is provided with guiding portions 10 and 20. By this means sand or the like and dirt is prevented 70 from entering the ends of the hollow body 3 under the parts 10 and 20, and accumulating in the body 3. The piston 5 is provided at both ends with recesses 8 and 9 for reducing its weight. The longer guide part 10 of the 75 piston has a longitudinal slot 11 in which engages a screw 12 fixed in the body 3. The slot 11 cooperates with the screw 12 to prevent the piston from turning on its axis and to also limit the stroke of the piston. 80

The hollow body 3 is provided at both ends with removable covers in which are respectively apertures 13 and 14, fitted with pipes 15 and 16. These pipes are connected to a pressure fluid vessel or a pump 17 supplying pressure fluid. When pressure fluid is admitted to the pipe 15, it forces the piston 5 from the position shown in Fig. 1 downward until the tube 1 is closed. When the pressure fluid is admitted to the pipe 90 16, the piston 5 will move upward into the position shown in Fig. 1. 85

The construction shown in Figs. 2 and 3, is substantially the same as that in Fig. 1, the only difference being that only the recess 8¹ of the pistons 5¹ can be subjected to the action of the pressure fluid. Consequently only the right hand end of the hollow body 3¹ is provided with an aperture 13¹ into which a pipe 15¹ is fitted that leads to 100 a pump or to a vessel 17¹ containing pressure fluid. As shown, the pressure fluid in this example is employed only for closing the well tube. The opening movement is effected by means of a screw 18¹ with hand 105 wheel 19¹ which screws in the cover 20¹ of the hollow body 3¹, and bears simply against the bottom of the recess 9¹ in the piston 5¹.

Having now described our invention, what we claim as new and desire to secure by Letters Patent is:—

1. A well tube closing apparatus comprising a cylinder having inlet and outlet openings, a well tube in communication with the inlet, a piston within the cylinder reciprocable across said openings, the piston in one position closing said openings and being 5 formed with a throughway therein adapted to be brought into communication with the openings in the cylinder and means for supplying a pressure fluid to the cylinder to actuate the piston, substantially as described.
- 10 2. A well tube closing apparatus comprising a cylinder having inlet and outlet openings disposed between the ends of the cylinder, a piston within the cylinder, extending across said openings, and formed with a 20 throughway normally in communication with the inlet and outlet openings of the cylinder, and means for supplying fluid pressure to the cylinder to actuate the piston to move the throughway from communication 25 with said openings and close the openings in the operation of the piston, substantially as described.
- 30 3. A well tube closing apparatus comprising a cylinder having inlet and outlet openings disposed between its ends, a piston within the cylinder, extending across said

openings, and formed with a throughway positioned nearer one end of the piston than the other and normally in communication with the inlet and outlet openings of the cylinder, said piston cutting off communication between the inlet and the cylinder in one position, and means for supplying pressure fluid to the cylinder to actuate the piston to close the inlet and outlet openings of the cylinder, substantially as described. 35

4. A well tube closing apparatus comprising a cylinder having inlet and outlet openings, a piston within the cylinder reciprocable across said openings, an unobstructed 40 throughway formed in the piston and laterally inclosed by a solid wall forming part of the piston, means for moving the piston in one direction to bring said throughway into communication with the openings in the cylinder, and fluid pressure means for moving the piston in the other direction to entirely close said openings. 45

In testimony whereof we have signed our names to this specification in the presence of 50 two subscribing witnesses.
